UNITED STATES PATENT OFFICE.

FRANK A. YOUNG, OF SULTAN, WASHINGTON, ASSIGNOR OF ONE-HALF TO KENNETH S. STARTUP, OF SULTAN, WASHINGTON.

POWER HAMMER.

Application filed October 10, 1924. Serial No. 742,854.

This invention relates to power operated forging hammers; and its object is to provide a machine of this character which will be of simple and inexpensive construction, efficient in operation and include mechanism whereby the hammer strokes may be completely controlled.

The invention consists in the novel construction, adaptation and combination of parts hereinafter described and claimed.

In the accompanying drawing,—

Figure 1 is a front elevation of a power hammer embodying the invention, partly broken away and partly in section to show details of construction; and Fig. 2 is a vertical section taken substantially on line 2—2 of Fig. 1.

In said drawing, the reference numeral 5 represents generally, a rigid frame which supports all of the working parts of the machine and is supported in an elevated position, as for example, upon the joists 6 of a building. As illustrated, said frame comprises a base element 7, and pairs of post elements 8 and 9 which are surmounted by a top element 10. 11 represents a hammer-head which is guided for vertical movements in a tube 12 which depends from the frame element 7.

Said hammer-head is secured to the lower end of a stem 13, preferably a board of hard wood, said stem passing upwardly between the complementary members 14—15 and 16—17 of two pairs of friction rolls.

These rolls are keyed or otherwise secured upon shafts 14¹, 15¹, 16¹ and 17¹ to which are also secured pulleys 14², 15², 16², and 17², about which, and a supplementary pulley 19, passes a power driven belt 20 whereby said friction rolls are rotated as indicated by direction arrows in Fig. 1.

The shaft 14¹ is journaled in eccentric sleeves, such as 21, mounted in bearings provided in the frame posts 8 and, in like manner, the shaft 16¹ is journaled in eccentric sleeves 22 mounted in bearings provided in the frame posts 9.

The shaft 15¹ of the roll 15, which is opposed to roll 14, is journaled in bearings provided in the lower ends of arms 23 which are swingably mounted upon the sleeves 22 in which the shaft 16¹ is journaled. The shaft 17¹ is journaled in the upper ends of arms 24, whose lower ends are swingably

mounted upon the sleeves 21 in which the shaft 14¹ is journaled. To compensate for the wear of the friction rolls 14 and 16, the eccentric sleeves thereof are suitably rotated and then secured in adjusted positions as by means of set screws 25. The arms 23 and 24 are coupled with each other by means of links 26 for coincident swinging movements which are effected through the medium of a connecting rod 27 by means of a lever 28 which is fulcrumed at 29 to the frame. The lever 28 extends to within easy reach of the operator standing upon the floor 30 adjacent to the machine anvil which is designated by 31.

Included in the invention are devices for engaging the stem 13 to retain the hammer at a selected elevated position.

As shown, said devices consist of a pair of blocks 32—32¹, one at each side of the hammer stem, mounted upon the machine frame for movement toward and from the stem. To such end, I provide headed screw bolts 33 passing through slots in the respective blocks and engaging in screw threaded holes provided in the frame. The blocks 32 may be controlled by any known or suitable means, as illustrated the controlling means comprises a lever 34 fulcrumed at 35 to the block 32 and intermediate its length is pivotally connected at 36 to ends of links 37 whose other ends are pivotally connected at 38 to the block 32¹.

39 represent springs connected, as shown, to the lever 34 and tending to act through the medium of the lever 34 and links 37 to cause the blocks 32 and 32¹ to be yieldingly held in disengaged relation with respect to the hammer stem.

To effect the engagement of the stem by the blocks the latter are influenced by regulating the lever and links above referred to by means of a pull rope 40 attached to the lever 34 and passing over a guide sheave 41 to within convenient reach of the operator.

The operation of the invention may be explained as follows: When the rope 40 is pulled down by the operator, the blocks 32 and 32¹ are closed against the stem 13 of the hammer to hold the same at a desired elevation as, for example, when work is being placed upon the anvil. When the lever 28 is actuated to draw the links 26 toward the left hand side of Fig. 1 the arms 23 and 24

are correspondingly swung to cause the friction roll 15 to be moved from the hammer stem 13 and the roll 17 to be brought against said stem which is thereby pushed against 5 the roll 16 whereupon the frictional action of the rolls on opposite sides of the stem act to elevate the hammer.

When the roll 17 is retracted by a reverse swing of the lever 28, such as will move the 10 links 26 toward the right hand, the hammer stem is first released from the rolls 16 and 17 and subsequently frictionally engaged between the rolls 14 and 15, resulting in the hammer being first allowed to fall by its 15 own gravitation and then accelerated in its downward travel by the power imparted thereto from the belt driven rolls 14 and 15. If it is desired to operate the machine to impart a series of rapidly delivered hammer blows, the lever 28 is manipulated to cause the opposing rolls 14—15 and 16—17 20 to be alternately brought into engagement with the hammer stem. Slower blows are provided by allowing the hammer to drop 25 by the force of gravitation and which blows accordingly have less momentum and striking effect than where the downward movement of the hammer is accelerated by power applied to the stem through the medium of 30 the belt driven rolls 14 and 15.

An important feature of the present invention resides in the provision of means for driving of all of the friction rolls directly by a single belt passing about pulleys 35 upon the respective roll shafts, thereby permitting the rolls individually to yield or slip for the purpose of obviating shocks and jars when either pairs of rolls is brought into engaging relation with the hammer 40 stem 13.

The operation of the invention will, it is believed, be understood from the foregoing.

While I have illustrated a construction now preferred by me, I do not wish to be understood as confining myself specifically thereto except as limited by the appended 45 claims.

What I claim is,—

1. In a power-hammer, a hammer-head, a stem therefor, two friction-rolls disposed at different elevations at opposite sides of said stem, shafts for said rolls, eccentric sleeves serving as bearings for the respective shafts, a frame in which said sleeves are mounted, means for securing the sleeves in adjusted 50 rotary positions, two pairs of arms pivotally supported at one end of each to the respective sleeves, shafts journaled in the free ends of said arms, friction-rolls carried by the last named shafts and arranged in opposed 55 relations with the first named rolls, a pulley provided on each of said shafts, a belt passing about the pulleys for driving all of the rolls, links connecting one pair of said arms with the other pair of arms, and means operatively connected with said arms for regulating the latter to cause the upper and lower 60 of said rolls selectively to be engaged with said stem for imparting upward and downward motion predeterminedly to the hammer-head.

2. In a power hammer, a hammer-head, a stem therefor, two friction-rolls disposed at different elevations at opposite sides of said stem, shafts for said rolls, a frame provided 75 with journal bearings for said shafts, two pairs of arms pivotally connected at one end of each to said frame, shafts journaled in the free ends of said arms, friction-rolls carried by the last named shafts and arranged 80 in opposed relations with the first named rolls, a pulley provided on each of said shafts, a belt passing about the pulleys for driving all of the rolls, links connecting one pair of said arms with the other pair of 85 arms, and means operatively connected with said arms for regulating the latter to cause the upper and lower of said rolls selectively to be engaged with said stem for imparting upward and downward motion predeterminedly to the hammer-head.

Signed at Sultan, Washington, this 10th day of September, 1924.

FRANK A. YOUNG.
